UNITED STATES PATENT OFFICE.

MATTHEW C. SHARPNECK, OF BOSTON, MASSACHUSETTS.

POWER-GENERATING TRACTION-WHEEL.

No. 852,301.

Specification of Letters Patent.

Patented April 30, 1907.

Application filed August 28, 1906. Serial No. 332,364.

To all whom it may concern:

Be it known that I, MATTHEW C. SHARPNECK, a citizen of the United States, residing at Boston, in the county of Suffolk and State of Massachusetts, have invented a new and useful Improvement in Power-Generating Traction-Wheels, of which the following is a specification.

My object is to provide a peculiarly durable and efficient fluid-pressure generating traction-wheel, of novel construction, for application, particularly, to a railroad car to utilize the traction force of the wheel, for generating, through the medium of compression-devices, air pressure for use as power. This generated power may be employed to supplement the motive force for running the car, or it may, if desired, be used in connection with air-pressure brake apparatus, or for other purposes.

My invention is illustrated in its preferred form of embodiment, in the accompanying drawing, in which—

Figure 1 is a view in side elevation, and partly in sectional elevation, of a car-wheel equipped with my invention; and Fig. 2, a view of the same partly in elevation, and partly in section, the section being taken at line 2, in Fig. 1, and viewed in the direction of the arrow.

The flanged rim-portion, 3, of my improved wheel is separate from the wheel-center and comprises two sections, 4 and 5, longitudinally separable which, as shown, are releasably secured together, as by bolts, 6. The rim-portion has formed within it an outer annular recess or runway, 7, concentric with relation to its tread, 8, and opening toward the center of the wheel into a larger concentric inner annular recess, 9, having side-walls or flanges, 10, inwardly projecting shoulders, 11, being provided between the recesses, 7 and 9, on opposite sides thereof, to serve as roller-bearing surfaces for roller-shafts, 12, hereinafter described. The wheel-center is represented at 13 and comprises a hollow hub, 14, carrying stuffing-boxes, 15, and journaled on a hollow axle, 16, concentric therewith, a series of fluid-pressure cylinders, 17, radiating from the hub and forming hollow spokes, and an annular rim-portion formed of spaced walls, 19, the wheel-center being slidably confined at its outer periphery within the flanged rim-portion, 3, between the walls, 10. The inner end of each cylinder is provided with a head, 20,

having an outwardly opening check-valve, 21, through which the air compressed in the cylinders, as hereinafter explained, is discharged into a chamber, 22, in the head, and thence through openings, 23, in its wall, into the hollow hub, from which it passes into the hollow axle through perforations, 24, in the latter, to be conveyed to the place of its use or to a storage-tank (not shown). Reciprocally confined in each cylinder is a piston-head, 25, containing a chamber, 26, into which air-inlet passages, 27, lead through the outer end of the piston-head, an inwardly-opening check-valve, 28, being provided in the inner wall of the piston-head, for permitting air to enter the cylinder from the chamber, 26, during the outward stroke of the piston.

Secured to each piston-head, as by a threaded connection, is a piston-rod, 29, terminating at its outer end in a stirrup, 30, in the opposite sides of which is journaled a roller-shaft, 12, carrying a roller, 31, which bears against the outer wall of the recess, 7. These roller-shafts, which extend beyond the supporting stirrups, are confined in the recess, 7, and bear at their projecting ends against the shoulders, 11, for the purpose of withdrawing the piston-heads from the cylinders, as hereinafter explained.

The piston-rods are held in alinement by roller-bearings, 32, journaled in eccentric bushings, 33, in the annular rim-portion of the wheel-center to embrace the piston rods on opposite sides. The supply of air to the cylinders to the piston-head is supplemented by air admitted through air-inlet openings, 34, provided in the walls of the cylinders.

It will thus be seen that by reason of the sliding bearing afforded between the annular rim-portion of the wheel-center and the walls, 10, the axle, during rotation of the wheel, is maintained in the same horizontal plane relative to the track, thereby causing the axle to be in permanent eccentric relation to the flanged rim-portion, 3. Thus in the travel of the cylinders about the axle from their uppermost to their lowermost positions, the respective piston-rods are forced inwardly into the cylinders, with the effect of compressing the air therein and discharging it into the hollow hub and thence through the axle, as hereinbefore explained. As the cylinders are carried from their lowermost to their uppermost positions, the piston-rods are withdrawn from the respective cylinders and air supplied to

the latter preparatory to its compression in the manner hereinbefore explained.

What I claim as new and desire to secure by Letters-Patent is,—

- 5 1. In a power-generating traction-wheel, the combination with the rim-portion containing an annular recess provided with side-walls and opening toward the center of the wheel, of a wheel-center of smaller diameter than the diameter of the recess, journaled on a hollow axle, and slidably confined at its periphery between said walls, said wheel-center having a hollow hub opening into said axle and carrying a series of radiating fluid-pressure cylinders provided with pistons actuated by the eccentric rotation of the rim relative to said axle.
- 10 2. In a power-generating traction-wheel, the combination with the rim-portion containing an annular recess provided with side-walls and opening toward the center of the wheel, of a hollow axle and a wheel-center of smaller diameter than the diameter of the recess, and comprising a hollow hub journaled on and opening into said axle, a series of fluid-compression cylinders radiating from said hub and adapted to discharge the compressed air into it, an annular circumferential portion at which the wheel-center is slidably confined between said walls, and pistons for said cylinders actuated by the eccentric rotation of the rim relative to said axle.
- 15 3. In a power-generating traction-wheel, the combination with the rim-portion containing an inner annular recess and an outer annular recess opening into each other with an interposed roller-shaft bearing-surface, of a hollow axle, a hollow hub journaled on said

axle and opening into it, a series of radiating fluid-compression cylinders mounted on said hub to discharge into it, pistons in said cylinders actuated by the eccentric rotation of the rim relative to the axle, said pistons carrying piston-rods provided with roller-shafts engaging said roller-bearing surface and rollers on said roller-shafts adapted to bear against the circumferential surface of the said outer recess, for the purpose set forth.

4. In a power-generating traction-wheel, the combination with the rim-portion, of a hollow axle, a hollow hub journaled on and opening into said axle, a series of fluid-compression cylinders radiating from said hub and adapted to discharge compressed air into said hub, and pistons in said cylinders having roller-bearing connection with said wheel-rim to be actuated by the eccentric rotation of the rim relative to the axle.

5. In a power-generating traction-wheel, the combination with the rim-portion, of a hollow axle, and a wheel-center comprising a hollow hub journaled on and opening into said axle, a series of fluid-compression cylinders radiating from said hub and adapted to discharge compressed air into it, pistons in said cylinders, piston-rods connected with the pistons and having roller-bearing connections with said wheel-rim to be reciprocated by the eccentric rotation of the rim relative to the axle, and guides in the wheel-center for said piston-rods, comprising rollers engaging opposite sides of the piston-rods.

MATTHEW C. SHARPNECK.
